HIS

UNITED STATES PATENT OFFICE

CHARLES S. BUSHNELL, OF ROCHESTER, NEW YORK; ASSIGNOR TO GENERAL RAILWAY SIGNAL COMPANY, OF ROCHESTER, NEW YORK

TRAIN-CONTROL SYSTEM

Application filed March 12, 1927. Serial No. 174,961.

This invention relates in general to a train control system, and has more particular reference to an intermittent inductive train control system of the alternating current type, including acknowledging and reset means.

In train control systems of the type referred to, it is usual to have spaced trackway inductors controlled in accordance with the traffic conditions and arranged to 10-15-20-25-30-35-40-45-50-55-60-65-70-75-80-85-90-95-100 influence a normally energized, alternating current, car-carried receiver, to cause such receiver to produce a train restricting influence, such as a brake application, or the like, unless prevented by the proper operation of an acknowledging device. If the train restricting influence be exerted it is then generally necessary to manually operate a reset device to restore the various parts to normal. In such systems the car-carried device usually comprises a main relay, with its energizing circuit tuned to the frequency of the current employed when its armature is picked up, so that after being re-energized, if its armature assume detracted position, the energizing circuit is thereby detuned, and removal of the trackway influence does not permit picking up of the armature of such relay, it being necessary, in some independent manner, to restore the armature to attracted position.

With the above and other considerations in mind, it is proposed, in accordance with this invention, to provide acknowledging and reset means for respectively preventing, for a temporary period, the dropaway of the main relay armature, upon de-energization of such relay, and for restoring the dropped away armature to attracted position.

More specifically stated, it is proposed in accordance with this invention to provide acknowledging and reset means including separate coils carried by the core of the main relay and operative, when energized, to move the armature of the main relay to, and to retain it in, attracted position. These separate coils can be energized by means of an acknowledging contactor through a circuit including front contacts of the main relay, and also by means of a specially positioned

reset contactor through a circuit independent of the main relay.

Further objects, purposes, and characteristic features of the present invention will appear as the description progresses, reference being had to the accompanying drawing, showing, solely by way of illustration, and in a wholly diagrammatic manner, one physical form which the invention can assume.

The single figure of drawing shows one embodiment of the present invention as applied to a train control system.

Referring to the drawing there is shown a railway track comprising track rails 1, divided into signalling sections, in a usual manner, by insulating joints 2, each block being provided with a wayside signal 3 of the semaphore type, and an inductor 4 positioned alongside the trackway adjacent the entrance end of each block. As indicated by dotted lines, the inductors are controlled by the signals to place them in active condition under caution and danger conditions of the particular block in question, and to place them in inactive condition under clear conditions of such block, the various control means for the signals and the inductors not having been shown or described as they are deemed non-essential to a complete understanding of the present invention.

Carried on the car, represented diagrammatically by wheels and axles 5, is a receiver having a core 6 carrying primary and secondary coils, P and S, the primary coils being included in a circuit comprising a source of alternating current 7, preferably of a frequency higher than commercial, such for example as 360 cycles per second, and a condenser 8, so chosen as to tune the circuit in question to the frequency of the current employed. The secondary coils S are included in a similarly tuned circuit including a condenser 9 and coils 10 carried on a core 11 of a main relay MR, the core 11, and the core 6 and inductor 4, all being of magnetic material and preferably laminated to cut down eddy current losses.

The main relay MR includes a pivoted armature 12, biased to its retracted position,

by a spring 13, and having contact fingers 14 and 15 electrically insulated from the body of the armature by insulating joints 16.

The organization includes a device, EPV, 5 arranged to control a car brake or a train restricting means of some character, and as shown in the drawing, is contemplated as being an electro-pneumatic device, normally energized, and which, on de-energization, 10 initiates the train restricting influence.

A reset contactor *Res* is provided and includes a manually operable rod 17, arranged to operate contact fingers 18 and 19.

An acknowledging device, designated as 15 *Ack* includes a spring biased depressible rod 20, arranged to operate contact fingers 21 and 22, the finger 21 moving with the rod, and the finger 22 being arranged, by means of a dash pot 23 and spring means 24, 24¹, 20 to slowly open after operation of the rod 20, in a well known manner, the time constant in the particular case in question being preferably about 15 seconds, whereby contact finger 22 does not break contact until about 15 25 seconds after operation of the acknowledging device.

Included on the core 11 of the main relay MR, as part of this system, are two reset and acknowledging coils 25, for a purpose to 30 be later described.

In order to simplify the wiring diagram and the description, symbols B and C have been employed to indicate opposite poles of a source or sources of direct current energy 35 such, for example, as a storage battery, which, under certain circumstances, could obviously likewise indicate the opposite instantaneous poles of an alternating current source or sources of electrical energy.

40 The various parts have been shown in the drawings in their normal conditions and positions, that is, the conditions and positions existing with the train proceeding in clear territory.

45 The primary and secondary coils, P and S, on the receiver are inductively related to each other so that coils 10 of main relay MR are normally energized by current induced in secondary coils S, to thereby hold 50 main relay armature 12 in picked up position.

The inductors and receiver are so positioned that the receiver passes over each inductor, in inductive relation thereto, through a small 55 air gap, and when the inductor is inactive, no appreciable effect is produced on the receiver, and the various instrumentalities remain in the positions and conditions shown 60 and described. When the inductor, however, is in active condition, corresponding to danger or caution traffic conditions, the flux distribution in the receiver core 6 is so modified as to reduce the amount of current flowing through the secondary circuit including 65

coils 10, to zero, or substantially so, whereby to de-energize main relay MR.

Assume, for the purpose of explanation, that the train is proceeding from a clear to a caution block, and that the engineer performs no act of acknowledgement when passing over the active inductor at the entrance to such block. In these circumstances, relay MR becomes de-energized, causing its armature 12 to drop away and thereby break the normal EPV energizing circuit through contact finger 15 and front contacts of relay MR, to thereby cause an automatic brake applica- 70 75

The dropping away of armature 12 of main relay MR detunes the secondary circuit so that resumption of flow of induced current in such circuit is insufficient to restore armature 12 and thereby re-energize EPV to release the brakes and allow the train to proceed, even though the secondary circuit were not taken through front contacts and contact finger 14 of the relay, making it a stick device which, when once de-energized so remains until otherwise restored. In this connection, it should be noted that detuning a circuit fed with high frequency alternating current, is substantially equivalent to opening a circuit fed with direct current. 80 85 90

It is necessary, for the train to proceed, to operate the reset device *Res* which is positioned so as to be operable only when the train is at a full stop, accomplished, for example, by positioning it to be accessible only from the ground. On depressing the reset rod 17, and energized circuit for the reset coils 25 is completed which can be traced from a source of energy B, contact finger 18 and back contact of *Res*, coils 25, to a source C, to thus attract the armature 12 and restore it to normal attracted position, whereupon the secondary circuit including the coils 10 becomes again complete, and also retuned, and the armature is retained by the normal flow of induced current through the secondary circuit even though the reset lever be restored to normal. In this connection it will be seen that it is necessary to restore the reset lever to normal, since when in its operated position, its contact finger 19 and front contact break 100 105 110 the normal energizing circuit for EPV. 115

Under the conditions assumed, namely, that the train is traveling from a clear to a caution block, if the engineer is alert and depresses the acknowledging rod 20 a short time prior to passing the active inductor 4, an acknowledging energizing circuit is completed for the acknowledging coils 25 which can be traced from a source C, the two coils 25 in series, contact finger 21 and back contact of *Ack*, contact finger 22 and front contact of *Ack*, and contact finger 15 and front contacts of relay MR, to a source B. This acknowledging energizing circuit retains the armature 12 in attracted position despite the 120 125 130

de-energization of the relay coils 10 and thus prevents de-energization of EPV and a consequent automatic brake application.

It should be noted that if the acknowledging contactor be tied down, or held down for too long a period, the slow opening contact finger 22 will open after a short time, so that, on encountering the next active inductor, de-energization of the main relay coils 10 will cause an automatic brake application, since the acknowledging energizing circuit for acknowledging coils 25 will have been broken at contact finger 22 and front contact of Ack.

From the above it will be seen that in a system of the character in question, an acknowledging and reset means has been provided which are properly protected against misuse, and will perform their desired functions in a most satisfactory manner.

The above rather specific description of one form of the invention, is shown solely by way of example, and is not intended, in any manner whatsoever, in a limiting sense. Obviously, the invention can assume many different physical forms, and is susceptible of numerous modifications, and all such forms and modifications are intended to be included by this application, as come within the scope of the appended claims.

Having described my invention, I now claim:—

1. In a train control system, a car-carried main relay having a normally energized circuit controlled in accordance with traffic conditions ahead, a brake applying device having an energizing circuit including a front contact of said relay and initiated when de-energized, a coil arranged when energized to place, and to maintain, the armature of the main relay in attracted position, means for only temporarily energizing the coil, and means for energizing the coil for an indefinite time while simultaneously breaking the energizing circuit for the brake applying device.

2. In a train control system, a car-carried main relay having a normally energized tuned circuit controlled in accordance with traffic conditions ahead, a brake applying device having an energizing circuit including a front contact of said relay and initiated when de-energized, a coil arranged when energized to place, and to maintain, the armature of the main relay in attracted position, acknowledging means capable of only temporarily energizing the coil through a circuit including a front contact of the main relay, and means for energizing the coil for an indefinite time while simultaneously breaking the energizing circuit for the brake applying device.

3. In a train control system, a car-carried main relay having a normally energized circuit controlled in accordance with traffic con-

ditions ahead, a brake applying device having an energizing circuit including a front contact of said relay and initiated when de-energized, a coil arranged when energized to place, and to maintain, the armature of the main relay in attracted position, acknowledging means, not affecting the energizing circuit of the brake applying device, for only temporarily energizing the coil, and means for energizing the coil for an indefinite time while simultaneously breaking the energizing circuit for the brake applying device.

4. In a train control system, a car-carried main relay having a normally energized tuned circuit controlled in accordance with traffic conditions ahead, a brake applying device having an energizing circuit including a front contact of said relay and initiated when de-energized, a coil on the core of the main relay for placing and maintaining the armature of the main relay in attracted position, means for only temporarily energizing the coil, and means for energizing the coil for an indefinite time while simultaneously breaking the energizing circuit for the brake applying device.

5. In a train control system, a car-carried main relay having a normally energized tuned alternating current circuit controlled in accordance with traffic conditions ahead, a brake applying device having an energizing circuit including a front contact of said relay and initiated when de-energized, a coil arranged when energized to place and maintain the armature of the main relay in attracted position, means for only temporarily energizing the coil, and means for energizing the coil for an indefinite time while simultaneously breaking the energizing circuit for the brake applying device.

6. In a train control system, a car-carried main relay having a normally energized circuit controlled in accordance with traffic conditions ahead, a brake applying device having an energizing circuit including a front contact of said relay and initiated when de-energized, a coil on the core of the main relay for attracting the armature of the main relay to attracted position, acknowledging means for only temporarily energizing the coil through a circuit including a front contact of the main relay, and means for energizing the coil for an indefinite time while simultaneously breaking the energizing circuit for the brake applying device.

7. In a train control system, a car-carried main relay having a normally energized tuned stick circuit controlled in accordance with traffic conditions ahead, a brake applying device having an energizing circuit including a front contact of said relay and initiated when de-energized, a coil on the core of the main relay for attracting the armature of the main relay to attracted position, acknowledging means, the operation of

which does not affect the energizing circuit of the brake applying device, for only temporarily energizing the coil, and means for energizing the coil while simultaneously breaking the energizing circuit for the brake applying device.

8. In a train control system, a car-carried main relay having a normally energized tuned alternating current circuit controlled in accordance with traffic conditions ahead, a brake applying device having an energizing circuit including a front contact of said relay and initiated when de-energized, a coil on the core of the main relay for attracting the armature of the main relay to attracted position, means for only temporarily energizing the coil, and means for energizing the coil while simultaneously breaking the energizing circuit for the brake applying device.

9. In a train control system, a main relay having a tuned energizing circuit controlled in accordance with traffic conditions ahead, a brake applying device having an energizing circuit including a front contact of the main relay and initiated when de-energized, a coil on the core of the main relay, a manually controlled acknowledging energizing circuit for the coil including a front contact of the relay and a slow opening contact finger, and

30 a manually controlled reset energizing circuit for the coil.

10. In a train control system, a main relay having a stick circuit controlled in accordance with traffic conditions ahead, a brake applying device having an energizing circuit including a front contact of the main relay and initiated when de-energized, a coil on the core of the main relay, a direct current acknowledging energizing circuit for the coil, including a front contact of the main relay and a slow opening contact finger and independent of the energizing circuit for the brake applying device, and a manually controlled direct current energizing reset circuit

45 for the coil.

In testimony whereof I affix my signature
CHARLES S. BUSHNELL.
